CLAIM

I claim the ornamental design for a display screen with a graphical user interface, as shown and described.

DESCRIPTION

The sole FIGURE is a front view of a display screen with a graphical user interface, showing my new design.

The outermost broken lines show a display screen and form no part of the claimed design. All other broken lines are for the purposes of illustrating portions of the display screen with graphical user interface and form no part of the claimed design.

1 Claim, 1 Drawing Sheet
